UNITED STATES PATENT OFFICE.

PETER FRANTZ, OF STERLING, ILLINOIS, ASSIGNOR TO FRANTZ MANUFACTURING CO., OF STERLING, ILLINOIS, A CORPORATION OF ILLINOIS.

DOOR LATCH.

Application filed August 28, 1925. Serial No. 53,010.

This invention relates to door latches, and more particularly to those ordinarily known at thumb latches, having a pivoted latch bar for engaging the strike piece on the doorway, 5 when the door is closed, and having a thumb piece for raising the latch bar.

Generally stated, the object of the invention is to provide a novel and improved construction, whereby two thumb pieces are employed, one at each side of the door, so that the door can be unlatched from either side thereof, and having means whereby the two thumb pieces are incorporated in a structural unit which can be easily inserted in the 15 door, preferably by merely boring a hole therein, as will hereinafter more fully appear.

It is also an object to provide certain details and features of construction and combinations tending to increase the general efficiency and desirability of a double thumb piece door latch construction of this particular character.

To the foregoing and other useful ends, 25 the invention consists in the matters herein-after set forth and claimed, and as shown in the accompanying drawings, in which

Figure 1 is a front elevation of a door latch involving the principles of the invention, showing the adjacent portions of the 30 door and the door frame.

Figure 2 is a detail horizontal section on line 2-2 in Figure 1.

Figure 3 is an enlarged plan view of one 35 of the thumb pieces.

Figure 4 is a side elevation of said thumb piece.

Figure 5 is a plan view of the blank from 40 which the mounting of the two thumb pieces is made.

Figure 6 is a side elevation of said mounting, after the blank is bent into shape.

Figure 7 is an enlarged vertical section on line 7-7 in Figure 1.

Figure 8 is a similar view showing the 45 parts in a different position.

Figure 9 is a detail section on line 9-9 in Figure 7.

Figure 10 is a plan view of the other 50 thumb piece.

Figure 11 is a side elevation of the thumb piece shown in Figure 10.

Figure 12 is a perspective of another part 55 of the mechanism.

As thus illustrated, the invention com-

prises the plates 1 and 2, which are provided with handles 3, and which are secured by screws 4 to the opposite sides of the door. At one side of the door there is a bracket piece 5 secured in place by screws 6, and 60 upon this bracket the latch bar 7 is pivotally held by a screw 8, or other suitable means. Said latch bar, it will be seen, is preferably bent to extend around the adjacent plate 2, and the end portion of the latch bar 7 is arranged in position to engage the strike piece 9, which is ordinarily fastened to the door frame, in the usual and well known manner, so that the latch bar will rise and then fall into locking engagement with said strike 70 piece, and thereby hold the door in closed position. The latch bar 7 also extends through a plate 10, fastened to the edge of the door, as shown, there being a slot in this plate to permit up and down movement of 75 the latch bar, and this plate and the strike piece have coinciding holes therein, so that a padlock can be inserted through both of them when it is desired to lock the door in closed position. 80

The mounting for the thumb pieces is made from the blank shown in Figure 5, and is bent into shape, as shown in Figure 6, so that it is tubular or cylindrical in shape. The downwardly bent portions 11 are provided with a pivot 12 upon which is mounted 85 the lifting piece 13 of the mechanism, and the portions 14 of the tubular mounting are inserted through slots in the plate 2 and are then riveted over to hold the tubular mounting in place. 90

The thumb piece 15 extends through an opening 16 in the plate 1, and has ears 17 which extend downwardly inside of said plate, whereby the lugs 18 of said thumb piece will bear against the outer surface of 95 the plate 1, and the thumb piece will be fulcrumed upon the lower edge of the opening 16 in said plate.

The other thumb piece 19 has an opening 100 therein, and has downwardly bent parallel portions 21, between which the inner end portion 22 of the other thumb piece is disposed. The edges 23 of the portion 21 bear against the inner surface of the plate 2, 105 while the outside lugs 24 of the thumb piece 19 bear against the outer side of said plate, thereby holding the thumb piece in place, and whereby this thumb piece is fulcrumed upon the lower edge of the opening 25 in the 110

plate 2, previously mentioned. The lifting piece 13 rests upon the inner end portion of the thumb piece 19, as shown, and when this thumb piece is depressed, the lifting piece will raise the latch bar. When the thumb piece 15 is depressed, its inner end portion will rise through the opening 25 and raise the lifting piece 13 and thus raise the latch bar.

10 In use, therefore, it is only necessary to bore a hole 26 in the door 27, as shown, and then to insert the more or less tubular sheet metal member 28, which latter forms the mounting, having the portions 11 and 14, previously mentioned. The other parts are assembled in the manner shown and described, and the latch bar 7 can be raised out of engagement with the strike piece 9 when it is desired to open the door, by means of 15 either thumb piece 15 or 19, in the manner shown and described. The working parts are all enclosed by the member 28, practically, as shown, within the thickness of the door, except the latch bar 7 and the outer 20 ends of the thumb pieces, as well as the outer end of the lifting piece 13, whereby the only alteration to the door is the boring of the hole 26, as previously explained.

25 The gap 29 formed in the upper side of 30 the member 28, at one end thereof, permits the lifting piece 13 to rise sufficiently, as shown in Figure 8, to lift the latch bar 7 out of engagement with the strike piece 9, in the desired manner. The gap between the lower edges 30 of the member 28 provides clearance for the inner end portion 22 of the thumb piece 15, as shown.

35 With the construction shown and described, it will be seen that the latch mechanism can be applied to doors of different thicknesses, and that the two thumb pieces are automatically relatively adjustable, so to speak, for doors of different thicknesses, inasmuch as the latching portions of the 40 two thumb pieces provide for such relative adjustment. In this way, the latch mechanism can be applied to doors of different thicknesses without any changing of the parts thereof, inasmuch as the two plates 1 45 and 2 are simply applied to a door of any particular thickness, and the housing 28 inserted as shown, and any difference in the thickness of the doors, within limits, will not necessitate any reconstruction or changing 50 of the parts of the mechanism. In other words, the thumb piece 19 will overlap the thumb piece 15 to a greater or less extent, depending upon the thickness of the door, and thus the two thumb pieces are, as stated, 55 automatically relatively adjustable, and in 60

a manner adjust themselves to the thickness of the door.

What I claim as my invention is:

1. A door latch for doors of different thicknesses, comprising a latch bar, a pivoted lifting piece for raising said bar, the bar and lifting piece having the same relation for doors of different thicknesses, a thumb piece for one side of the door, a thumb piece for the other side of the door, one thumb piece extending over the other below said lifting piece, and means to fulcrum and support each thumb piece, so that each thumb piece has the fulcrum point thereon for doors of different thicknesses, whereby depression of either thumb piece will cause said lifting piece to raise the latch bar.

2. A structure as specified in claim 1, comprising a mounting upon which said lifting piece is pivoted, said mounting being inserted through the door and forming a housing for said lifting piece and the inner end portions of said thumb pieces, within which mounting the lifting piece and the inner end portions of the thumb pieces are free to rise and fall.

3. A structure as specified in claim 1, one thumb piece having an opening through which the adjacent end portion of the other thumb piece is free to rise, substantially as shown and described.

4. A structure as specified in claim 1, comprising an outer plate secured to each side of the door to provide fulcrums for the two thumb pieces, with a slot in one plate for permitting said lifting piece to raise the latch bar, each plate having a fixed fulcrum point on its allotted thumb piece, both plates being removable without removing said lifting piece, and handles the upper ends of which are secured to said plates below and out of engagement with said fulcrums.

5. A structure as specified in claim 1, comprising a sheet metal housing inserted through the door to enclose said lifting piece and the inner ends of said thumb pieces, and an outer plate secured to one end of said housing.

6. A structure as specified in claim 1, comprising plates secured at opposite sides of the door, providing fulcrums for the two thumb pieces, so that the thumb pieces are automatically relatively adjustable for doors of different thicknesses, means between and independent of said plates for pivotally supporting said lifting piece, and handles separate from said fulcrums.

Specification signed this 18 day of Aug., 1925.

PETER FRANTZ.
